UNITED STATES PATENT OFFICE.

FRANK M. BASHELIER, OF JENKINTOWN, PENNSYLVANIA, ASSIGNOR TO KEYSTONE TYPE FOUNDRY, OF PHILADELPHIA, PENNSYLVANIA, A CORPORATION OF PENNSYLVANIA.

PRESSMAN'S REGISTER-TABLE.

1,057,373.

Specification of Letters Patent. Patented Mar. 25, 1913.

Application filed August 27, 1910. Serial No. 579,224.

To all whom it may concern:

Be it known that I, FRANK M. BASHELIER, a citizen of the United States, residing at Jenkintown, in the county of Montgomery and State of Pennsylvania, have invented 5 certain new and useful Improvements in Pressmen's Register-Tables, of which the following is a specification.

The object of my said invention is to provide 10 a "register" table for the use of pressmen in making up and adjusting page forms in printing offices, by the use of which the type may be adjusted in each form and the several page forms arranged in the printing 15 form so that the printing on each page will be in perfect alinement with that of the other pages and the lines on opposite sides of the sheet register perfectly with each other, and one color form register with other 20 color forms so that the several colors will properly register and blend, and it consists in various improvements in the details of construction, and arrangement of parts, whereby a very efficient table for such purpose is provided, all as will be hereinafter 25 more fully described and claimed.

Referring to the accompanying drawings which are made a part hereof and on which similar reference characters indicate similar 30 parts, Figure 1 is a top or plan view of a pressman's register table of my improved construction, Fig. 2 a side elevation of the same, Fig. 3 an end elevation, and Fig. 4 a detail section on the dotted line 4-4 in 35 Fig. 3.

In said drawings the portions marked A represent the frame, and C the electric lights. The frame A consists, in the main, of a box-like structure preferably composed 40 of wooden sides with a bottom a and a top frame consisting of side rails a' and a'' , end rails a^3 and a^4 and a central cross rail a^5 . Between the central cross rails a^5 and each 45 end rail are mounted plate glass panels A' which serve as the main top of the table. This box-like structure is supported on legs a^6 , preferably of angle iron, which embrace the corners of the box and are bolted thereto by bolts a^7 extending through the angles of 50 said legs and the side pieces of the box, thus securing the box rigidly together and making the structure rigid and durable. Doors a^8 hinged at their bottom edges to swing 55 downwardly are mounted in the front of the box to give convenient access to the in-

terior, for the purpose of placing and adjusting the electric lamps. Said lamps C are preferably incandescent electric bulbs of ordinary construction mounted in sockets secured to the bottom a of the box, electrically 60 wired and connected with a power current supply wire in the ordinary or any approved form. Said lamps are controlled by an ordinary, or any approved, form of switch, such as the switch s of the push-button type 65 shown, by which the current may be turned on and off in the usual way. In the ends of said box are formed openings a^9 for ventilation.

In use, the table being fitted up and arranged as shown in Figs. 1 and 2, the pressman places a proof of the printed form, or forms, over the glass top on one side or the other of the table, securing it on said top by thumb tacks which may be inserted in the rails a^3 , a^4 and a^5 , and by manipulating the pages, is able to determine the adjustment necessary to secure a correct alinement and registry between the lines of the various pages and the lines on the opposite sides of 80 the same sheet and also the proper adjustment to secure the relative position of different color forms necessary to secure the correct blending of the colors in color printing.

The top rails of the box are preferably 85 removable, as indicated, so that after they are used until their surfaces become non-effective to hold the thumb tacks by reason of the numerous perforations therein they may be removed and others substituted, as will be 90 readily understood.

Having thus fully described my said invention, what I claim as new and desire to secure by Letters Patent, is:

1. A pressman's register table comprising 95 a frame box-like structure, angle-iron supporting legs which embrace the corners of said structure and are bolted thereto, a frame with removable sections formed to receive glass panels mounted on said box-like structure, glass panels mounted in said frame, electric lamps mounted in said box, doors in the side of said box for access to the interior, and means for turning on and off the lights, substantially as set forth.

2. A pressman's register table comprising 100 a frame box-like structure secured together at its corners by angle-irons bolted to each side thereof, said angle-irons extending 105 downwardly a distance to serve as legs to 110

support said box-like structure, a frame mounted on said box-like structure composed of rails formed to receive and support glass panels, plate glass panels mounted in said frames, electric lights mounted in said box-like structure, and means for manipulating them, substantially as set forth.

In witness whereof, I have hereunto set

my hand and seal at Washington, District of Columbia, this 20th day of August, A. D. 19 nineteen hundred and ten.

FRANK M. BASHELIER. [L. S.]
